THERMIONIC AMPLIFIER

Prafulla Kumar Chatterjea and Charles Thomas Scully, London, England, assignors, by mesne assignments, to International Standard Electric Corporation, New York, N. Y., a corporation of Delaware

Application January 12, 1944, Serial No. 517,974
In Great Britain January 13, 1943

6 Claims. (Cl. 179—171)

1
The present invention relates to thermionic valve circuits and in particular to audio frequency amplifying circuits such as are used in radio receivers.

The invention makes use of the properties of devices known as thermistors.

Thermistors are thermosensitive resistance elements having a temperature coefficient of resistance which may be either positive or negative and which is moreover many times the corresponding coefficient for a pure metal such as copper. This property renders thermistors particularly suitable for a variety of special applications in electric circuits.

Various different materials are available for the resistance element of a thermistor, these various materials having different properties in other respects; as one example, a resistance material having a high negative temperature coefficient of resistance comprises a mixture of manganese oxide and nickel oxide, with or without the addition of certain other metallic oxides, the mixture being suitably heat treated.

Thermistors have been employed in two different forms: (a) known as a directly heated thermistor and comprising a resistance element of the thermally sensitive resistance material provided with suitable lead-out conductors or terminals, and (b) known as an indirectly heated thermistor comprising the element (a) provided in addition with a heating coil electrically insulated from the element. A directly heated thermistor is primarily intended to be controlled by the current which flows through it and which varies the temperature and also the resistance accordingly. Such a thermistor will also be affected by the temperature of its surroundings and may therefore be used for thermostatic control and like purposes with or without direct heating by the current flowing through it. An indirectly heated thermistor is chiefly designed to be heated by a controlling current which flows through the heating coil and which will usually, but not necessarily, be different from the current which flows through the resistance element, but this type of thermistor may also be subjected to either or both of the types of control applicable to a directly heated thermistor.

More detailed information on the properties

of thermistors will be found in an article by G. L. Pearson in the Bell Laboratories' Record, Dec. 1940, page 106.

2
The present invention is concerned with the improvement of the performance of audio frequency reproducing systems, particularly those used in radio receivers of the cheaper kinds. In such receivers particularly in compact types, it is necessary to economise in space, cost, and power consumption, and therefore the loudspeaker and the power available to operate it are small. The low frequency end of the speech frequency band is accordingly attenuated acoustically, and may not be reproduced at all. In these circumstances it is useless to raise the level of the low frequency end of the range electrically, as very little improvement acoustically could be produced this way.

It is well known that if several harmonics of a fundamental frequency are simultaneously applied to the human ear acoustically at sufficiently high level, the fundamental is generated therein on account of asymmetric distortion in the sound transmission. Use is made of this property to improve the apparent quality of cheap radio receivers or other apparatus employing an audio frequency reproducing system, by generating harmonics of the low frequencies in the power output stage (or anywhere else in the voice-frequency part of the circuit) and these are supplied to the loudspeaker which transmits them at a reasonable level. The ear then manufactures the fundamentals from which the harmonics were derived, and the absence of the low frequencies, which would otherwise cause the reproduction to sound poor, is not noticed.

The arrangements previously used for generating harmonics have involved the use of valves and filters. The object of the present invention is to simplify the production of the harmonics by the use of a directly heated thermistor.

According to the invention, therefore, there is provided an electrical reproducing circuit wherein the loudspeaker or other reproducing device is operated by a circuit comprising a thermionic valve amplifier characterised in this, that a directly heated thermistor is connected to the amplifier in such manner that currents of signal frequencies pass through the thermistor, the

characteristic of which and the operating point thereon being so chosen that the thermistor generates harmonics of signal frequencies at the lower end of the voice frequency range for application to the reproducing device.

The invention will be described with reference to the accompanying drawing, in which:

Fig. 1 shows a schematic circuit diagram of part of a radio receiver according to the invention;

Fig. 2 shows thermistor characteristics employed to explain the action of Fig. 1; and

Fig. 3 shows a schematic circuit diagram of another embodiment of the invention.

Fig. 4 shows a thermistor connected with a low pass filter.

Fig. 1 shows the last voice-frequency power stage of a radio receiver, and will be seen to be a particular case of Fig. 1 of British application No. 12,884/42. A thermionic valve V has the loudspeaker LS connected in series with the anode, and the resistance element R of a directly heated thermistor T, which may be shunted by a condenser C is connected in series with the cathode. The purpose of this condenser is explained below, but its use is not essential, and it may be omitted if desired. X_3 is the grid leak resistance, and K is a blocking condenser of suitable capacity through which the incoming signals are applied to the control grid of the valve V from other parts of the radio receiver (not shown).

Fig. 2 shows two typical characteristic curves for a directly heated thermistor having a negative temperature coefficient of resistance. The curve i shows the relation between the resistance value of the element R and the current flowing through it, and the curve v shows the relation between the resistance and the voltage across it. The v curve indicates that there is a critical maximum M above which the voltage cannot rise, and that there are two possible values of resistance corresponding to any voltage less than this maximum value. The part LM of the curve v corresponds to an unstable condition; and the current tends to increase spontaneously if a voltage equal to or greater than the critical value is applied.

The thermistor should be so chosen that when no signals are being received, the current and resistance in the circuit of Fig. 1 correspond to the point P on the i curve which lies on an ordinate PN which cuts the stable part of the v curve at a point Q. The condenser C (if used) is chosen so that it effectively short-circuits the thermistor except for the frequencies near the low end of the signal frequency range. Thus when a low signal frequency is received, the anode current fluctuates accordingly and the fluctuations are permitted by the condenser to pass through the thermistor. The point P in general describes an oval curve as indicated owing to the delay in response of the thermistor, this oval curve tending to coincide practically with the curve i for the lowest frequencies. The point Q describes a similar oval curve which represents voltage variations which are fed back to the control grid of the valve to be mixed with the incoming signals. Owing to the non-linear response of the thermistor, harmonics will thus be generated and mixed with the signals, and will be reproduced by the loudspeaker.

Although in Fig. 1 the thermistor is connected in series with the cathode of the valve for the purpose of generating harmonics of the signal frequencies present, similar results can be ob-

tained by connecting the thermistor in other parts of the amplifier which feeds the loudspeaker.

In Fig. 3 is shown part of the final amplifier of a radio receiver comprising two thermionic valves V₁ and V₂ the cathodes of which are biased in the usual way by means of appropriate series resistances X each shunted by a condenser Q. The loudspeaker is connected in series with the anode of the last valve to the high tension supply E, and the anode of the valve V₁ is supplied from E through the resistance element R of a directly heated thermistor T and through a resistance R₁. The anode of V₁ is connected to the control grid of V₂ through a blocking condenser K and the usual grid leak resistance R₂ is provided. The thermistor may be shunted by the condenser C whose purpose is as described above.

The thermistor should be so chosen that with the normal anode current of the valve V₁ the operating point is at Q in Fig. 2 on the stable portion of the characteristic curve. The harmonics generated in the thermistor will produce corresponding variations of the anode voltage of V₁ which are supplied directly to the control grid of V₂ and thence to the loudspeaker.

According to another variation the thermistor T together with its shunting condenser C (if used) may be removed from the position shown in Fig. 3, and connected instead to replace the whole or part of the resistance R₂. In this case, since there is no direct current flowing through the thermistor the operating point will be at S in Fig. 2. Harmonics will be generated partly on account of the curvature of the characteristics and partly on account of the fact that both half-waves will produce a reduction of the thermistor resistance, which is equivalent to the introduction of even harmonics.

It will be understood that the condenser C does not sharply divide the range into portions so that only certain low frequencies generate harmonics. Actually the effect produced is that the harmonics are produced at greater amplitude as the frequency becomes lower, which is the condition desired, and at some not too high predetermined frequency (say several hundred cycles per second) the generation of harmonics has become inappreciable.

If it is desired to limit the frequency range over which harmonics are generated very sharply, the condenser C may be dispensed with and a suitable low pass wave filter provided as shown in Figure 4 through which the thermistor is connected to the circuit of Fig. 1 or Fig. 3. This filter can be designed so that frequencies above a certain predetermined frequency substantially do not reach the thermistor, so that harmonics cannot be generated by them.

It will be noted also that the fundamental low frequencies tend to be reduced in intensity by the arrangements of Fig. 1 or 3 but this is not of much importance since the loudspeaker could not reproduce them any way.

It will be evident that the thermistor can be arranged as described with reference to Fig. 1 or 3 in connection with any part of the audio frequency amplifier of the radio set. In other words, it is not essential, in the case of Fig. 1, for example, that the thermistor should be connected in series with the cathode of the last valve. It would operate equally well if connected in series with any other audio frequency valve, and similarly for Fig. 3. Furthermore, a thermistor with a positive temperature coefficient of resistance may be used, since it will have a curved charac-

teristic adapted to generate harmonics, though it will not have a negative slope in any part. Accordingly the operating point may be chosen anywhere on the characteristic. Also, the final utilisation means connected to the output of the amplifier need not be a loudspeaker; it could be a pair of head-phones or other electromechanical device.

What is claimed is:

1. An electrical reproducing circuit of the type wherein an electro-acoustical transducer is operated by current derived from a thermionic valve amplifier, including a directly heated thermistor connected in series with the cathode of said thermionic valve so that the cathode current of said valve flows therethrough, the thermistor characteristics and the operating point thereon being so chosen that said thermistor generates harmonics of signal frequencies at the lower end of the voice frequency range for application to said reproducing device.

2. Electro-acoustical transducing circuit including an electronic amplifier, a sound reproducer in the output circuit thereof, and a thermistor having a negative temperature coefficient and adjusted so that in the absence of signals the current which flows therethrough corresponds to a point on the stable part of the voltage-current characteristic curve of said thermistor, said thermistor being connected in series with the cathode of said thermionic valve so that the cathode current of said valve flows therethrough, whereby said thermistor generates harmonics of signal frequencies at the lower end of the voice frequency range for application to said reproducing device.

3. An electrical reproducing circuit of the type wherein an electro-mechanical sound reproducing device is operated by the output of a thermionic valve amplifier, including a directly heated thermistor connected to said amplifier in such manner that currents of signal frequencies pass through said thermistor, the characteristic of said thermistor and the operating point thereon being so chosen that the thermistor generates harmonics of signal frequencies at the lower end of the voice frequency range for application to said reproducing device, also including a condenser shunting said thermistor, the capacity of said condenser being chosen substantially to short-circuit said thermistor at and above a predetermined frequency.

4. An electrical reproducing circuit adapted to be connected with an electro-mechanical sound reproducing device comprising a thermionic

valve having a cathode, anode and a control grid, a directly heated thermistor connected to said valve in such manner that currents of signal frequencies pass through said thermistor, the characteristic of said thermistor and the operating point thereon being so chosen that the thermistor generates harmonics of signal frequencies at the lower end of the voice frequency range for application to said reproducing device, the thermistor being connected in series between the control grid and the cathode of the valve.

5. An electrical reproducing circuit of the type adapted to be connected with an electro-mechanical sound reproducing device comprising a thermionic valve having a cathode, anode and control grid, a directly heated thermistor connected to said valve in such manner that currents of signal frequencies pass through said thermistor, the characteristic of said thermistor and the operating point thereon being so chosen that the thermistor generates harmonics of signal frequencies at the lower end of the voice frequency range for application to said reproducing device including means connected to said thermistor for preventing appreciable generation of harmonics for frequencies above a predetermined frequency applied to said thermistor.

6. An electrical reproducing circuit of the type wherein an electro-mechanical sound reproducing device is operated by the output of a thermionic valve amplifier, including a directly heated thermistor connected to said amplifier in such manner that currents of signal frequencies pass through said thermistor, the characteristic of said thermistor and the operating point thereon being so chosen that the thermistor generates harmonics of signal frequencies at the lower end of the voice frequency range for application to said reproducing device, and a low pass filter so connected with the thermistor as to pass through said thermistor substantially only currents below said predetermined frequency.
